UNITED STATES PATENT OFFICE.

FREDRIC EDWARD WHITHAM, OF OXENHOPE, ENGLAND.

GRINDING-MILL.

SPECIFICATION forming part of Letters Patent No. 736,657, dated August 18, 1903.

Application filed January 13, 1902. Serial No. 89,754. (No model.)

To all whom it may concern:

Be it known that I, FREDRIC EDWARD WHITHAM, engineer, a subject of the King of Great Britain, residing at Moorhouse, Oxen-
5 hope, in the county of York, England, have invented certain new and useful Improvements in Grinding-Mills, of which the following is a specification.

This invention relates to grinding-mills; 10 and it consists in the novel construction and combination of the parts hereinafter fully described and claimed.

In the drawings, Figure 1 is a sectional side elevation of my improved grinding or reducing apparatus, showing grinding-disks suitable for breaking stones or as a first or preliminary breaker. Fig. 2 is a plan view of apparatus shown at Fig. 1, with top disk or cover removed. Fig. 3 is a side elevation of 20 bottom or rotary disk.

In constructing my improved grinding apparatus I employ a suitable cylindrical metallic shell or casing *a*, near the upper part of which work the grinding-disks *b c*. (See first 25 or preliminary breaker, shown at Figs. 1, 2, and 3.) The top or fixed disk *b* is bolted or otherwise secured to the shell *a* and acts as a cover for same. A circular opening *d* is provided in the center of this stone, having 30 conical sides *e* projecting upward, which serve as a hopper by which the mineral or material is admitted to be ground. The inner or grinding surfaces *f* of these disks are corrugated or fluted in a desired manner.

The bottom or rotary disk *c* is mounted or pivoted upon the vertical driving shaft or spindle *g* and has a conical center piece *h*, of a greater angle than the conical inlet *e* of the fixed disk *b*. This stone is also corrugated or fluted in a similar manner, and both may be made of cast-iron, chilled iron, or manganese steel, with or without plates upon their grinding-surfaces, as desired. The driving-shaft *g* rests upon an adjustable foot-step 45 *j* and is supported by suitable bearings *k* and driven by bevel-wheels *m*, shaft *n*, and pulley *p* upon said shaft (not shown) from any suitable source and operates to drive the bottom or rotary disk *c* by means of arms *r*, 50 keyed upon said shaft *g* and resting or fitting between dogs *s*, cast upon or otherwise attached to the under side of the said disk *c*.

w is an opening provided in the outer shell or case, preferably one-quarter of its circumference and area, the floor of the grinding-chamber inclining at this part to facilitate such discharge. 55

In order to compensate for uneven density or weight in the materials or metal or wear of the grinding-disks, I provide a suitable balancing arrangement, as follows: Upon the side of the bottom or rotary disk *c* 4 in each set or underneath said disk and near its outer periphery I provide or form a suitable *T*-groove *22* with suitable gaps or openings to admit of the insertion of a suitable plate *23* and bolts *24* underneath this groove *22*, and bolted to the aforesaid plate is a suitable weight *25*. By slackening the nuts *26* the plate *23* and weight *25* are adjusted within the said groove *22* so as to displace the center of gravity to any required extent and in any desired direction. The nuts are then tightened, so maintaining the whole in perfect balance. 65

The amount of reduction by the disks may 70 be regulated by moving the said disks nearer to or farther from each other. This operation is accomplished by mounting the vertical driving-shaft upon the adjustable foot-step *j*. This foot-step consists of a suitable sleeve *32*, 75 screwed or threaded upon the outside and working within an internally-screwed casting *33* upon the machine-case *a*. The shaft end contains a hardened-steel peg, (not shown,) which rests upon suitable hardened-steel 80 washers, also contained within the sleeve *32*. Upon this screwed sleeve *32* is a worm-wheel 85 *34*, actuated, when required, by a worm *35* upon a longitudinal shaft *36*, receiving motion by means of bevel-gear *37*, vertical shaft *38*, and hand-wheel *39*. By these means the worm-wheel *34* upon being operated acts upon the 90 screwed sleeve *32* and either raises or lowers the driving-shaft, as desired. Also suitable angle or flanged rings *40* are employed, one 95 attached to or cast upon the bottom or rotary disks *c* 4 and the other to the floor *41* of the grinding-chamber *42*. These rings *40* are for confining the ground material, preventing same from interfering with the working parts 100 and assisting in its discharge from the machine.

Having now particularly described and ascertained the nature of my said invention and

the manner in which the same is to be performed, I declare that what I claim is—

In a grinding-mill, the combination, with a stationary grinding-plate *b* having an annular flat portion and a conical inlet *e* at its center part, said inlet being smaller in diameter at its top than at its bottom where it joins onto the flat portion of the said plate, of a driving-shaft, a revoluble grinding-plate *c* pivoted on the said shaft and free to rock thereon, said plate *c* being provided with a conical and pointed center portion *h* which projects with-

in the said inlet *e* and having a flat annular portion around the said center portion, all the said opposed flat and conical portions being 15 provided with ribs or corrugations *f*, and a driving connection between the said shaft and the plate *c*.

In testimony whereof I hereunto affix my signature in the presence of two witnesses. 20

FREDRIC EDWARD WHITHAM.
